United States Patent

Des. 241,593
Patented Sept. 28, 1976

241,593

TOILET PAPER COVER

James W. Wriede, 3466 Pinewood Drive,
West Homestead, Pa. 15120

Filed Oct. 26, 1971, Ser. No. 168,797

Term of patent 14 years

Int. Cl. D23—02

U.S. Cl. D6—97

FIG. 1.

FIG. 2.

FIG. 3.

FIG. 1 is a perspective view of a toilet paper cover;
FIG. 2 is a front elevational view thereof; and
FIG. 3 is a vertical sectional view taken on line 3—3 of FIG. 2, the portions of a wall, a toilet paper roll holder and a roll of toilet paper are shown in broken lines for illustrative purposes only.

I claim:

The ornamental design for a toilet paper cover, substantially as shown and described.
